(57) **CLAIM**

The ornamental design for a dual mode attenuating earplug, as shown and described.

DESCRIPTION

FIG. 1 is a back perspective view of a dual mode attenuating earplug according to my new design,

FIG. 2 is a top view thereof,

FIG. 3 is a bottom view thereof,

FIG. 4 is a left side view thereof,

FIG. 5 is a right side view thereof,

FIG. 6 is a back view thereof; and,

FIG. 7 is a front side view thereof.

The dotted line detachable cord member shown in FIG. 1 is for illustrative environmental purposes only and forms no part of the claimed design.
